UNITED STATES PATENT OFFICE.

ALFRED EDWARD PEPPERCORN, OF FORBES, NEW SOUTH WALES, AUSTRALIA.

AUTOMATIC ADDITIONAL-AIR VALVE FOR COMBUSTION-ENGINES.

1,343,375.

Specification of Letters Patent. Patented June 15, 1920.

Application filed July 29, 1918. Serial No. 247,190.

To all whom it may concern:

Be it known that I, ALFRED EDWARD PEPPERCORN, subject of the King of Great Britain and Ireland, residing at Forbes, New 5 South Wales, Australia, have invented new and useful Improvements in Automatic Additional-Air Valves for Combustion-Engines, of which the following is a specification.

10 This invention relates to that type of automatic "additional air" valve for combustion engines in which a cylinder, one end of which is open to atmosphere, and the other end of which is in communication with the inlet manifold of the engine, is fitted with a spring pressed piston, and said piston, when moved against said spring 15 responsively to variations in the subatmospheric pressure in the manifold, opens an air admission vent through which additional air enters to the manifold, diluting therein the fuel mixture which has been inducted from a carburetor or a mixing valve.

20 To obtain the necessary exactness of control and a graduated admission of air into the manifold proportionate to the degree of depression therein during running, the control piston, the movement of which is 25 responsive to variations in the degree of subatmospheric pressure in the manifold, should be of considerable area, should be always subject to full atmospheric pressure of the induction on its inner face, and 30 to obtain uniform regulation of its movement by means of a loading spring it should have a long stroke. The air admission valve should be of relatively small dimensions and of a type which permits of delicate 35 setting and adjustment. Such an air valve having its movements controlled by such a piston will then be automatically opened 40 and closed proportionately to the pressure changes in the manifold without "dithering" and will be automatically fully opened 45 to admit a full flow of air for braking purposes when the throttle valve is fully closed so as to prevent entrance of air or fuel mixture to the manifold via the carburetor 50 or the mixing valve.

An additional air valve according to my invention is illustrated in the accompanying drawing, in which Figure 1 is a longitudinal sectional elevation, in which the valve 55 is shown closed; Fig. 2 is a partial longitudinal sectional elevation, in which the

valve is shown in the full open position; Fig. 3 is a side elevation with a fragment broken away to show the valve seat; Fig. 4 is a semi-diagrammatic view illustrating 60 the mounting of the valve on the induction manifold of an automobile engine; and Fig. 5 is a fragment sectional elevation illustrating an alternative arrangement of the regulating spring.

65 The valve casing is differentially bored on the same center, to a large diameter 10 in its forward end, and to a small diameter 11 in its rear end. The larger diameter bore 10 should be at least double the diameter of 70 the smaller diameter bore 11, but may be very much larger. A piston 12, preferably formed with labyrinthine packing rings 13 is finished to a neat sliding fit in the large bore chamber 10. A rearward concentric 75 trunk or plunger extension 14 of this piston is turned and finished to a neat fit for the small bore chamber 11. A tubular air passage 15 is bored through the plunger 14 and the piston 12, to place the back end of 80 the small bore chamber 11 in communication with the front end of the large bore chamber 10. At its front end the fitting is closed by a nipple piece 16, which is adapted to be screwed into a tapped hole in the 85 engine manifold between the carburetor or mixing valve and the cylinder inlet valves, as for instance as indicated in Fig. 4, so that the front end of the chamber 10 is placed in communication with the engine 90 manifold. The extreme rear end of the casing terminates in a screwed stud 18; this stud may be integral with it, or it may be separate and screwed into it. The stud 18 serves to carry a yoke 19 which may be set 95 wherever required by means of two jam nuts 20 and 21. The narrow bore chamber 11 is ported at either side. The slot portions 23 of these ports extend through the middle length of the chamber 11, and rearwardly they are extended as narrow taper slits 24, the ends of which terminate a little forward of the rear end of the chamber 11, so that the plunger does not commence 100 to uncover them until it has moved a short 105 distance off the valve seat 25. At the base, the bore of the chamber 11 is finished to a conical valve seating 25, and the end of the plunger 14 is turned conical and ground to the face 25, so as to form a tight closure 110 therewith when the valve is in the closed position shown in Fig. 1. When the valve

is so closed, air cannot pass from atmosphere through the ports 23, 24 and the tubular passage 15 to the manifold. A bar yoke 26 is passed through a close fitting hole 5 drilled through the plunger 14, and said yoke extends through the lateral ports 23, and carries on its ends the ends of two helical loading springs 28; the other ends of these springs are attached to the arms of 10 the adjustable yoke 19. The tension of the piston loading springs 28 is set by adjusting the nuts 20 and 21 on the stud 18. 29 are air holes through the casing wall, behind the rear end of the piston 12, to allow 15 free ingress of air to the annular space in the chamber 10 rearward of the piston when the piston moves forwardly responsive to variations in subatmospheric pressure in the engine manifold.

20 The overall length of the fitting may be shortened by omitting the loading spring adjusting yoke 19 and the stud 18 which carries it, also omitting the bar yoke 26, and using in place thereof a helical loading 25 spring 30 in compression set in front of the piston 12, as shown in Fig. 5. The ends of the spring 30 take their abutments respectively against the forward end of the piston 12 and against the back of the nipple cap 30 16, and the tension of the spring is adjusted by screwing the nipple 16 more or less into the casing; the nipple is secured in adjusted position by means of jam nut 32.

In operation, when the engine is idle, the 35 piston loading springs 28, (or 30 as the case may be) are tightened up to hold the valve in the closed position in which it is shown in Fig. 1. Air cannot then pass from atmosphere through the valve. After the engine 40 has been started, the loading spring tension is adjusted so that the induction suction acting on the forward side of the piston 12 permits the superior pressure of atmosphere to force the piston forward and compress the 45 loading spring, thereby opening the valve at the seat 25. Further forward movement of the plunger 14 takes place when the engine is accelerated, and the taper slits 24 in the side of the chamber 11 are then gradually 50 opened, and atmospheric air enters therethrough, passes over the end of the trunk and flows through the tubular passage 15 into the chamber 10 and thence through the nipple 16 to the induction manifold 31. Forward movement of the piston 12 is permitted 55 by free admission of atmospheric air behind it through the air holes 29. As the suction in the manifold increases as the engine is further accelerated, the loading springs 28 60 (or 30 as the case may be) are flexed proportionately and permit the piston and plunger to move forward gradually further opening up the ports 24, 23. The initial tension on the loading springs must be adjusted so 65 that movement of the valve is insufficient to

admit too much additional air as if that happened a point would be reached at which the cylinder charge would not explode efficiently. The spring loading must be adjusted for each engine under running conditions, and 70 the ports 24-23 should be trimmed in width to graduate the air admission so that the desirable degree of dilution of the normal charge is effected for all ranges of engine speed and throttle adjustment by the air 75 admitted through said ports. In effecting the final adjustment for best efficiency, the loading springs are first relaxed to the tension at which the engine displays a tendency to backfire under load, and they are then 80 tightened slightly, thus insuring a fuel mixture slightly denser than required for certainty of explosion under load.

It will be found in practice that with approximately correct adjustment of the 85 spring loading and appropriate trimming of the ports 24-23, running air will be taken through them in sufficient quantity to dilute the engine charge to the desired extent unless it is initially abnormally rich. 90

In the case of a car having the device fitted to its engine, when the car is in motion and the throttle is closed, the depression in the manifold will be in excess of the reaction of the loading springs, and the piston 95 and plunger will therefore move forward full stroke, thereby admitting free air through the ports 24-23 and the passage 15 to the manifold, so that the suction demand of the cylinders is satisfied and a braking effect is obtained without waste of fuel through the carburetor, and without drawing lubricating oil up into the cylinder past the piston rings and thereby fouling the 100 cylinders.

What I claim as my invention and desire to secure by Letters Patent is:—

1. An air admission valve automatically responsive to fluctuations in sub-atmospheric pressure in the manifold of a combustion 11 engine, comprising two coaxial intercommunicating cylinder chambers of substantially different diameters with an air vent at the base of the larger chamber and a closed end on the smaller chamber, a piston fitted to 11 said larger chamber, a plunger extension on said piston fitted to said smaller chamber, the piston and plunger having a tubular passage therethrough, a nipple connection for an engine manifold on the end of the 12 said larger chamber, a valve face on the plunger end and a corresponding valve seating in the end of said smaller chamber, slotted ports in the side of the smaller chamber, a draw yoke carried by said plunger and 12 having its ends projecting through said slotted ports, a stud extension rearward of the smaller chamber, a carrier yoke adjustably mounted thereon, and a pair of helical springs in tension having their ends respec- 13

- tively attached to said draw yoke and said carrier yoke.
2. An air admission valve automatically responsive to fluctuations in subatmospheric pressure in the manifold of a combustion engine, comprising a differential bore cylinder with a free air vent to the atmosphere at the base of the larger bore, a piston and a plunger extension of substantially smaller diameter thereon, said piston and plunger being fitted respectively to the two bores of the cylinder, a valve face on the plunger end, a corresponding valve seating adapted to be closed thereby in the end of the small bore of the cylinder, means including a spring and a device for regulating its tension for opposing atmospheric pressure acting behind said piston while a condition of partial vacuum exists in the cylinder bore at the front end thereof, the side of the small bore of the cylinder being provided with air ports adapted to be progressively uncovered by the plunger in its forward motion therein.
3. An automatic air admission valve comprising a cylinder concentrically bored on a large diameter at one end and on a substantially smaller diameter on the other end, with a free air vent intermediate said large and small bores, means for fitting the

larger end of said cylinder in communication with the induction manifold of a combustion engine, a spring loaded piston movable in the larger bore of said cylinder responsive to fluctuations in sub-atmospheric pressure in said induction manifold, means for adjusting the tension of said loading spring, a plunger concentric with said piston and forming a rearward extension thereof and fitted to the smaller bore of said cylinder, a valve face on the end of said plunger and a corresponding valve seating fitted to said face in the end of the smaller cylinder bore, the ends of the respective cylinder bores being connected by passages extending through said plunger and piston and spring tension adjusting means, and the side of said smaller cylinder bore having an air admission port adapted to be gradually uncovered by said plunger in its forward movement therein.

In testimony whereof I have signed my name to this specification in the presence of two subscribing witnesses.

ALFRED EDWARD PEPPERCORN.
